(57) **CLAIM**

The ornamental design for a multi-functional educational toy ball with rings and side discs bead, as show and described.

DESCRIPTION

FIG. 1 shows a perspective side view where the bead is slightly tilted to the right showing my new design;
FIG. 2 shows a perspective view of the bottom half of the bead, shown separately for ease and clarity of illustration;
FIG. 3 shows a perspective side view of the top half of the bead, shown separately for ease and clarity of illustration; and,
FIG. 4 is a cross-sectional view taken from line 4-4 of FIG. 1.

The screw threads and inside of the bead do not form part of the claimed design.
